HAMMOCK

Hyman Mover, Newton North, Mass.

Application February 1, 1938, Serial No. 188,117

4 Claims. (Cl. 5—94)

The present invention relates to a means and method of suspending a hammock, chair or seat intended more particularly to be used for infants and small children when riding in vehicles as for instance automobiles and the like.

The device is adapted to be placed either over the back of a seat or it may be suspended and supported in other ways, for which of course other supporting elements may be included. Particularly in connection with the suspension of baby hammocks in automobiles, it is necessary not only to be able to suspend the hammock easily and conveniently in the machine, but also the suspension should be of such a nature and type that the infant is disturbed as little as possible.

In the present invention the hammock may be suspended at the back of the front seat with a top hook or strap passing over the top of the seat and resting securely on the top shoulder. In such an arrangement the hammock is positioned between the front and back seats and is suspended in a horizontal position in such a manner that it will be freely supported to allow for the up and down motion of the car to be minimized as will be explained later. The hammock is further supported in such a manner as to prevent any side wise or end swing as the car may be jolted to one side or another.

Further advantages and improvements in the present device will be readily understood from the specification below taken in connection with the drawing which shows an embodiment of the invention, in which:

Figure 1 shows a vertical elevation of the hammock as attached to a seat of an automobile.

Figure 2 shows an end view looking at Figure 1.

Figure 3 shows a perspective view as seen from one corner of the hammock.

Figure 4 shows a modification of a detail indicated partly in fragmentary sections of an element shown in the other figures, and, Figure 5 shows an edge view of the detail shown in Figure 4 looking from the bottom upwards of Figure 4.

In the arrangement indicated in the drawing, the hammock proper itself is shown at 1. This may be of any well known type of material and is preferably made with a metallic frame 2 the top of which is covered by the hammock itself and stitched in place as indicated by the stitches 3. The hammock itself may be of any well known type and as indicated in the present invention is shaped somewhat as a basket. To the top rim 2 of the hammock there is attached a U-shaped bracket indicated in the drawing at 4 passes from

the inner top edge of the hammock to which it is riveted and pivoted at 5 around the bottom of the hammock and at the other side in the same fashion thus forming a wide U shaped element with side supports or arms 6 and 7. Extending from a point near the lower ends of the arms or forks 6 and 7 is a hinged link 10 composed of the link members 8 and 9, the link 8 being pivoted to the arm 6 at the point 11 which is almost down to the base of the arm 6. This link 10 extends diagonally upward and has its portion 9 similarly pivoted at 12 to the metallic frame element 2. The pivot in the link 10 between the elements 8 and 9 is indicated at 13 over which a ring 14 may be provided to assure that the link 10 will not collapse. There are two such links, one on each side of the hammock, both of which are similarly numbered as indicated in Figure 1.

On the base of the bracket 4 there is provided a pair of holes on both ends near the bend to the side pieces 6 and 7. Through these holes there pass rods or bars 15 and 16 which extend upright parallel with the sides of the brace 4 and held in place in this position through the holes in the brace 4 through which the rods 15 and 16 pass, and also by means of the eyes 17 and 18 which are fastened to the side pieces 6 and 7. The rods or bars 15 and 16 are curved substantially at right angles above the eyes 17 and 18 as indicated by the element shown in dotted lines 19 in Figure 2. This curved portion 19 emerges into the hooks or supports 20 which are preferably covered with rubber sheathing 21, 24, lying against and over the shoulder of the seat 30 as indicated in Figure 2. At the lower end of the rod 16 and 17 below the brace 4 and surrounding them are springs 22 which are short helical springs and positioned in such a manner as to bear against the under surface of the brace 4 as indicated in Figures 1 and 2.

Beyond the position of the spring, the rods 16 and 17 curve inwardly substantially at right angles as indicated by 23 in Figure 3 and form a right angle arm beyond this point as indicated in Figure 3 which is covered by means of the rubber sheathing 24 so that the end angle element 25 is positioned to grip and rest firmly against the material of the back seat.

The hammock may be used as indicated in the perspective drawing of Figure 3, that is attached at the back of the seat in an automobile. In this case the hammock will occupy a horizontal position with the U shaped supporting bracket having its base resting upon the springs as indicated. Any motion of the car that tends to move the

hammock up or down will be absorbed by the action of the spring in this position. In combination with this the angle arm 25 with the rubber sheathing 24 and the clamping arm, hold the 5 frame firmly against the seat, so that the hammock while firmly fastened in position is sufficiently free to avoid undesired vibrations.

In place of the link shown in Figures 1, 2 and 3, wherein the ring 14 keeps the link arms 8 and 9 10 in a rigid extensible position, the arrangement shown in Figures 4 and 5 may be employed. In this case the link is composed of a U channeled member 40 between the sides of which is inserted a single bar element 41. The bar element 41 is 15 provided with a slot 32 which has one portion which is straight but inclined to the edge of the bar and the end portion curved in an arch as indicated at 33. A pin 34 passes through the both walls 35 and 36 of the U shaped channel and is 20 fixed rigidly thereto. This pin passes through the slot 32 and is arranged in such a position that the bars 41 and 40 may be inclined at an angle with one another or be held fast in one continuous straight line. In the first position where the 25 two elements are inclined to one another, the pin 34 rides around the curved portion 33 of the slot, while the end of the bar 41 indicated as 37 rotates within the U shaped channel. When it is desired to make one straight element of the 30 two links, the links 40 and 41 are brought into alignment and pushed towards one another. In this position the slot acts as a wedge to wedge, the element 41 in the portion indicated by 38 between the pin 34 and the end wall of the channel 40 making thereby a rigid joint which locks the two elements in place and prevents them from being pulled apart easily. The edge of the channel element also in combination with the edge of the bar 41 furnishes a rigid element which assumes the position of the rods 8 and 9 as indicated in Figures 1, 2 and 3.

In the device just described it will be noticed that the bracket itself which extends from the front of the hammock around the base is the sole 45 support of the hammock itself through the rivets at the top edge as indicated at 5 and at the links as indicated at 12. It will also be noted that this bracket is supported freely for up and down motion upon the spring 22 and that in effect the 50 whole hammock is free to move up and down under the spring action upon which it yieldingly rests or floats.

In place of supporting the spring element by means of compression, the arrangement may be 55 such that the spring 22 may act as a suspending element for suspending the rod 16. In this case the suspension element or spring will at one end be held by the back supports as for instance, the bars 20, and at the other end the spring will in 60 turn support the bracket 6 in such a way as to allow the whole hammock also to float freely up and down.

Having now described my invention, I claim:

1. Means for supporting a hammock yieldingly 65 to a vehicle seat comprising a frame element to which the hammock is attached and which supports said hammock, a U shaped bracket having its open ends attached to the frame of the hammock near adjacent corners of said frame and supporting said frame, said bracket being positioned at one side of the hammock and having a foldable link extending from the bottom of the bracket to the forward part of the hammock, a pair of rods one positioned at either side of the bracket and 70 means attaching each of said rods to the bracket 75

to provide free up and down motion of the bracket with respect to said rods, means for resiliently supporting the bracket on the rods comprising at each side a helical spring loosely surrounding the rod and interposed between the bottom of the U-shaped bracket and a supporting stop on the rod and means provided at the extremities of said rods for supporting the same on a vehicle seat. 5

2. A collapsible baby's hammock adapted to be hung over the seat of an automobile, comprising 10 a rectangular metallic frame, a fabric forming the hammock body having a rectangular open top fitting over and attached to said rectangular frame, a square cornered U shaped bracket, means pivoting the U shaped bracket at the open 15 ends of the sides of the U to said frame near adjacent corners thereof, a pair of folding links, each pivoted at one end to the sides of said frame to which the U shaped member is pivoted but away from said corners and at the other end to 20 the sides of the U shaped bracket near the corners thereof, a pair of members having mid-sections arranged parallel to the sides of said U shaped brackets with top portions adapted to hang over the automobile seat and a lower portion spacing the hammock away from the seat, and means for supporting said U shaped bracket on said members including spring means positioned to act vertically between the U shaped 25 bracket and said members. 30

3. A collapsible baby's hammock adapted to be hung over an automobile seat, comprising a rectangular metallic frame, a fabric forming the hammock body having a rectangular open top fitting over and attached to said rectangular frame, a square cornered U shaped bracket, means pivoting the U shaped bracket at the open 35 ends of the sides of the U to said frame near adjacent corners thereof, a pair of folding links each pivoted at one end to the sides of said frame 40 to which the U shaped member is pivoted but away from said corners and at the other end to the sides of the U shaped bracket near the corners thereof, a pair of members having mid-sections arranged parallel to the sides of said U 45 shaped brackets with top portions adapted to hang over the automobile seat and a lower portion spacing the hammock away from the seat, said mid-section at its top end having means attaching it to the side of said U shaped bracket and 50 permitting free vertical motions with respect thereto and said mid-section at its lower end passing through the cross bar of said U shaped element and a helical spring about the lower end of said mid-section supported between the bottom of said U shaped bracket and the lower portion 55 of said member spacing the hammock from the seat.

4. A collapsible baby's hammock adapted to be hung over an automobile seat, comprising a 60 rectangular metallic frame, a fabric forming the hammock body having a rectangular open top fitting over and attached to said rectangular frame, a square cornered U shaped bracket, 65 means pivoting the U shaped bracket at the open ends of the sides of the U to said frame near adjacent corners thereof, a pair of folding links each pivoted at one end to the sides of said frame to which the U shaped member is pivoted but 70 away from said corners and at the other end of the sides of the U shaped bracket near the corners thereof, a pair of members having mid-sections arranged parallel to the sides of said U shaped bracket with top portions adapted to 75

hang over the automobile seat and a lower portion spacing the hammock away from the seat, said lower portion comprising an angle element positioned horizontally to said vertical element, and means for supporting said U shaped bracket on said members including spring means

resting at its lower end on said angle element and at its upper end engaging under the cross bar of the U shaped bracket for freely supporting said U shaped bracket to permit free vertical motion of said hammock against said spring.
